VISCOUS FLUIDS TRANSFER FUNNEL
OR THE LIKE

Daniel S. Williams, 47 S. 3rd St., Reading, Pa.

Filed Oct. 20, 1965, Ser. No. 87,656

Term of patent 3½ years

(Cl. D44—29)

FIG. 1 is a perspective view of the new ornamental design of a viscous fluids transfer funnel or the like, in accordance with the present invention;

FIG. 2 is a bottom view thereof; and

FIG. 3 is a sectional view taken on lines 3—3 of FIG. 2.
I claim:

The ornamental design for a viscous fluids transfer funnel or the like, as shown.
